[57] CLAIM

The ornamental design for a watch case, as shown and described.

DESCRIPTION

FIG. 1 is a top plan view of a watch case showing my new design,

FIG. 2 is a right side elevational view thereof,

FIG. 3 is a left side elevational view thereof,

FIG. 4 is a rear elevational view thereof,

FIG. 5 is a front elevational view thereof,

FIG. 6 is bottom plan view thereof,

FIG. 7 is sectional view taken from line VII—VII in FIG. 1 and

FIG. 8 is top, left side and rear perspective view thereof.

The broken line showing of a watch band in FIG. 8 is for illustrative purposes only and forms no part of the claimed design.

FIG. 4

FIG. 3

FIG. 1

FIG. 2

FIG. 5

FIG. 6

FIG. 7

FIG. 8
